RAINWATER DOWNSPOUT TROUGH

Virgil A. Sturm, 415 Cedar, Nashua, Iowa 50658

Filed June 14, 1973, Ser. No. 370,166

Term of patent 14 years

Int. Cl. D23—01

U.S. CL. D23—1

FIG. 1

FIG. 2

FIG. 3

FIG. 4

FIG. 5

FIG. 1 is a top plan view of the rainwater downspout trough showing my new design;

FIG. 2 is a side elevation view thereof;

FIG. 3 is an end elevation view thereof as seen from the left-hand end of FIG. 2;

FIG. 4 is an elevational view thereof as seen from the right-hand end of FIG. 2; and

FIG. 5 is a bottom plan view thereof.

I claim:

The ornamental design for a rainwater downspout trough, substantially as shown.
